Primary Examiner — Darlington Ly*Assistant Examiner* — Nasim Abdulaziz Ali(74) *Attorney, Agent, or Firm* — Andrus Intellectual Property Law, LLP(57) **CLAIM**

The ornamental design for an electric bicycle, as shown and described.

DESCRIPTION

FIG. 1 is a front elevation view of an electric bicycle embodying our showing my new design;
FIG. 2 is a rear elevation view thereof;
FIG. 3 is a right side elevation view thereof;
FIG. 4 is a left side elevation view thereof;
FIG. 5 is a top plan view thereof;
FIG. 6 is a bottom plan view thereof; and,
FIG. 7 is a front and left side perspective view thereof.
The broken lines shown in the figures depict portions of the electric bicycle that form no part of the claimed design.
